UNITED STATES PATENT OFFICE.

PHILIP PIETROBONO, OF EAST HARTFORD, CONNECTICUT.

ROCKING-CHAIR ATTACHMENT.

1,346,675.

Specification of Letters Patent. Patented July 13, 1920.

Application filed October 8, 1919. Serial No. 329,279.

To all whom it may concern:

Be it known that I, PHILIP PIETROBONO, a subject of the King of Italy, and a resident of the United States, residing at East Hartford, Connecticut, have invented new and useful Improvements in Rocking-Chair Attachments, of which the following is a specification.

The present invention relates to improvements in mechanically operated fan mechanism and more particularly to means to utilize the energy of a rocking chair or other movable seat or manually operated structure in the form of mechanical means to actuate fan mechanism whose force may be directed upon the operator.

A further object of this invention is to provide such a device which may be easily and quickly attached or detached, to or from a rocking chair, movable seat or other manually operated structure of conventional type.

Various other objects and advantages of the invention will become apparent during the continuance of the following description:

In the drawings:

Figure 1 is a view in side elevation showing my invention applied to a rocking chair of conventional type.

Fig. 2 is a view in top plan.

In actual practice my invention consists of a supporting stand 10 which may be mounted on rollers 11 and which carries at a certain point a standard 12, the said stand being held rigid by any suitable or ordinary means. A rocking chair or other movable device 13 may be arranged on the stand 10, as shown in the drawings and carries a diagonal supporting rod 14 as at 15.

The rod 14 in turn carries a stud or pinion 16 which rotatably supports a beveled gear wheel 17. The rod further carries a bracket 18 for a fan member 19, the operating shaft

of the fan extending through the bracket and being provided with a pinion 20 to 45 mesh with the beveled gear 17.

In order to rotate the wheel 17 and in turn actuate the fan member, I provide the wheel 17 with a connecting rod 21, one of the rods being pivotally connected thereto as 50 at 22. The other end of the rod 21 is pivotally connected to a rocker arm 23 as at 24 so that upon proper movement of the rocker arm the rod 21 will cause rotation of the wheel 17 and the consequent operation of 55 the fan member.

A stud 25 carried by the standard 12 operates in a slot 26 of the arm 23, thus providing a pivot for the arm; while the other end of the arm is connected to the rocking 60 chair as at 27.

From the above it will be readily seen that upon motion of the rocking chair in the usual manner, the arm 23 will be rocked upon the pivot 25 causing a compound reciprocal and oscillatory movement of the rod 21 and the consequent rotation of the wheel 17 and the fan member.

What is claimed is:

The combination with a support equipped 70 with a standard and having a rocking chair mounted thereon, of a supporting rod rigidly fixed to and projecting above the chair, a beveled gear mounted upon the rod, a bevel pinion meshing therewith, a bracket 75 fixed to the rod and supporting said pinion, a fan operable with the pinion, and a lever mounted upon the standard and connected with said bevel gear and said chair whereby movement is imparted to the bevel gear 80 when the chair is set in motion.

PHILIP PIETROBONO.
